FIREARM

George S. Lewis, New Haven, Conn., assignor to
Winchester Repeating Arms Company, New
Haven, Conn., a corporation of Maryland

Application May 14, 1936, Serial No. 79,673

13 Claims. (Cl. 42—69)

This invention relates to an improved firearm, and one of its objects is to provide a simple and reliable firearm which may be produced at a low cost for manufacture.

5 Another object is to provide a firearm having a superior firing mechanism of a character which is economical to produce and which is reliable and effective in operation.

A further object of the present invention is to 10 provide a superior firearm in which the cocking of the firearm members is accomplished by an improved construction and arrangement of parts.

Still another object is to provide a superior 15 firearm of the breakdown type, in which the breakdown action thereof is facilitated by the firing mechanism.

A still further object is to provide a firearm 20 having superior safety means for automatically guarding against the accidental or unintentional discharge of the firearm.

Other objects and advantages will appear to 25 those skilled in the art from the following, considered in conjunction with the accompanying drawings.

With the above and other objects in view, as will appear to those skilled in the art from the following, considered in conjunction with the accompanying drawings, the present invention includes all features disclosed therein which are novel over the prior art, and not elsewhere claimed by me.

In the accompanying drawings:

Fig. 1 is a broken view in side elevation of a 35 breakdown gun embodying the present improvements;

Fig. 2 is a view thereof, partly in side elevation and partly in vertical longitudinal section, and showing the butt- and barrel-units in their normal positions immediately after the gun has been fired;

Fig. 3 is a broken view corresponding to Fig. 2, but showing the barrel-unit in its breakdown position with reference to the butt-unit;

45 Fig. 4 is a view similar to Fig. 2, but showing the firing mechanism cocked preparatory to firing;

Fig. 5 is a vertical sectional view taken on the line 5—5 of Fig. 4;

50 Fig. 6 is a similar view taken on the line 6—6 of Fig. 4;

Fig. 7 is a broken horizontal sectional view taken on the line 7—7 of Fig. 4;

55 Fig. 8 is a perspective view of the barrel-locking member;

Fig. 9 is a similar view of the operating-lever; and

Fig. 10 is a broken perspective view showing the firing mechanism and associated parts.

The particular breakdown firearm herein 5 chosen for the illustration of the present invention includes two major units pivoted together for relative movement. The rear unit of the firearm may for convenience of description be designated as the "butt-unit" and comprises as its main 10 features a frame 20 and a buttstock 21 rigidly secured to said frame. The complementary front unit of the firearm, designated for convenience of description as the "barrel-unit," comprises as its main elements a barrel 22 and a forestock 23 re- 15 movably secured to the under-side of the said barrel. The forward portion of the frame 20 is of substantially U-shaped form in cross-section and includes a bottom-wall 24 and spaced-apart side-walls 25—25 providing an upwardly-opening re- 20 cess or pocket 26. The recess or pocket 26, just referred to, is adapted to receive a rectangular barrel-coupling lug 27 depending from the under-side of the barrel 22 adjacent the rear end of the latter and forming a rigid feature thereof. 25

The forward edge of the barrel-coupling lug 27 is formed with a transverse forwardly-opening notch 28, the forwardly-facing semicircular wall of which engages with and bears upon the periphery of a fulcrum-pin 29 extending transversely 30 of the frame 20 adjacent the forward end of its trough-shaped portion and having its respective opposite ends rigidly supported in the complementary side-walls 25—25 thereof.

The complementary side-walls 25—25 of the 35 frame 20, as well as the bottom-wall 24 thereof, merge at their rear ends into a tubular portion 30 having a forwardly-facing standing-breach 31 against which the rear end of the barrel 22 abuts when the firearm is closed. Extending rearwardly from the substantially-tubular portion 30 of the frame are an upper butt-attaching tang 32 and a lower butt-attaching tang 33 respectively secured at their rear ends to a vertical spacing-block or pillar 34. 45

Mounted upon the upper surface of the tubular portion 30 of the frame 20 is an operating-lever 35 having a downwardly-extending cylindrically-contoured operating-head 36 projecting downwardly through and bearing in a substantially-vertical passage 37 formed in the upper wall of the tubular portion 30 of the frame 20. The said operating-head 36 forms a unitary feature of the operating-lever 35 and is formed in its lower end with a coupling-notch 38 (Fig. 7) receiving the 50 55

upper end of an operating-finger 39 upstanding from a barrel-locking member 40. The said barrel-locking member 40 is mounted for pivotal movement upon a transverse pivot-pin 41 extending crosswise of the tubular portion 30 of the frame 20 and rigidly supported by the respective opposite side-walls thereof.

The barrel-locking member 40 is provided with a forwardly-extending locking-nose 42 normally 10 entering a locking-notch 43 formed in the rear edge of the barrel-coupling lug 27 before referred to. For the purpose of yieldingly urging the locking-nose 42 of the barrel-locking member 40 into the locking-notch 43 so as to hold the 15 butt-and-barrel units in their aligned positions, in which they are shown in Figs. 1, 2 and 4, the said barrel-locking member 40 is formed in its rear face, near its lower end, with a rearwardly opening spring-receiving pocket 44 receiving a helical 20 compression-spring 45 having its rear end bearing against and looped around a transverse pivot-pin 46 mounted in the tubular portion 30 of the frame 20.

Mounted for pivotal movement upon the transverse pin 46 is an L-shaped tensioning-lever 47 having an upstanding-arm 48 and a relatively-long forwardly-extending arm 49. The arm 49 of the tensioning-lever 47 fits within a longitudinal notch 50 formed in the lower right corner of 30 the barrel-coupling lug 27 and is depressed by the upper wall of the said notch for the purpose of 35 tensioning a helical firing-spring 51 in a manner as will hereinafter appear.

The helical firing-spring 51 encircles a firing-pin or plunger 52, the forward end of which is reduced in diameter to form a firing-point 53 projectable through a passage 54 in the standing-breech 31 to effect the firing of a shell in the chamber of the barrel 22 in a manner usual in firearms. The said firing-plunger or member 52 is formed with a stop-flange or abutment 55 which is adapted to abut against the rear face of a stop-finger or abutment 56, which latter also acts on occasion as a shifter for the said firing-plunger. The said firing-plunger extends through the stop-finger 56 with freedom for relative reciprocating movement with respect thereto. The stop-finger 56 extends laterally from a sheet-metal slide 57 extending laterally with and to one side of the firing-plunger 52 and which is formed at its rear end with a tensioning-finger 58 extending crosswise of the firearm, like the stop-finger 56 before referred to. By virtue of its two fingers 56 and 58, the slide 57 serves when moved 50 forwardly to tension the firing-spring 51 and when moved rearwardly to bodily shift the firing-plunger 52 and its firing-spring 51 in the same direction. For purposes of description, the said slide will be termed a "shifting" slide or member.

60 The tensioning-finger 58 is formed with a key-hole-shaped notch 58^a, with which an annular clearance groove 58^b in the firing-plunger 52 may be aligned during the installation of the said firing-plunger in the tensioning-slide 57. The 65 rear portion of the firing-plunger 52 just forwardly of its contracted neck-portion 59 bears in the enlarged inner portion of the notch 58^a. The parts are so proportioned, however, that the neck-portion 59 of the firing-plunger does not come 70 into registration with the notch 58^a under operating conditions, so that the firing-plunger is prevented from laterally escaping from the tensioning-finger 58.

The neck-portion 59 terminates at its rear end 75 in a rearwardly- and inwardly-tapered annular

cocking-head 60 which on occasion is adapted to be hooked back of a cocking-finger 61 laterally offsetting from a sheet-metal sear generally designated by the numeral 62. In addition to the cocking-finger 61, the sear 62 includes a downwardly-and-forwardly-extending arm 63 terminating in a laterally-bent finger 64.

The rear end of the sear 62 extends into a clearance-notch 65 formed in the side of the spacing-pillar 34 and is pivotally secured to the said spacing-pillar by a screw-stud 66. The said sear 62 is yieldingly urged in the direction required to engage its finger 64 with the adjacent upper surface of a trigger 67 and to engage its cocking-finger 61 with the cocking-head 60, by a double-armed sear-spring 68 looped around the screw-stud 66 before referred to. The said sear-spring 68 has its lower arm 69 hooked over the arm 63 of the sear and has its opposite arm 70 bearing against the under side of the upper tang 32.

The trigger 67 above referred to is mounted for pivotal movement in a vertical slot 71 in the lower tang 33 of the frame and is hung therein upon a transverse pivot-pin 72 mounted in the said tang and extending transversely across the said slot therein. In addition to having a usual depending finger-piece 73, the trigger is formed with a rearwardly-extending arm 74 against the upper surface of which rests the laterally-extending finger 64 of the sear 62. The arm 74 of the trigger 67 has pivoted to its rear end by means of a rivet 75 an upwardly-extending safety-arm or member 76 which when rocked forwardly as indicated in Fig. 2 is adapted to move upwardly into a longitudinal slot 77 formed in the upper tang 32 of the frame 20 and which when swung to its rearmost position, as shown in Figs. 3 and 4, is adapted to engage with the under side of the upper tang 32 when an effort is made to pull the trigger 67. The bottom edge of the said safety-arm 76 comes to rest against the upper surface of the lower tang 33 and limits the reverse swinging movement of the trigger 67.

For the purpose of shifting the safety-arm or member 76 into either one of its two extreme positions just referred to, the said arm is provided in its upper end with a coupling-notch 78 receiving the cylindrically-contoured lower end of a coupling-finger 79 depending from a safety-slide 80 mounted for reciprocating movement upon the upper face of the upper-tang 32 and extending downwardly into the longitudinal slot 77 therein. For the purpose of yieldingly holding the safety-slide 80 and hence the safety-arm 76 in either one of its two extreme positions, the depending coupling-finger 79 of the said slide is provided with a laterally-extending detent-pin 81 engaging with the free rear end of a crimped detent-spring 82 secured by means of a screw 83 to the under side of the upper tang 32 to one side of the slot 77 60 therein.

For the purpose of supporting and guiding the shifting-slide 57 and hence the firing-plunger 52, the said slide has pivotally attached to its lower edge, adjacent its rear end, a supporting-link 84 which is also pivotally mounted upon the pivot-pin 72 upon which the trigger 67 is mounted.

In addition to acting as a support and guide for the shifting-slide 57 and hence for the firing-plunger 52 the link 84 acts as a safety-locking member by being provided with a rearwardly-extending safety-locking finger 85 which is adapted on occasion to fit under the forwardly-extending safety-locking finger 86 of the pivotal safety member 76. It will be noted that the 75

upper surfaces of the safety-locking finger 85 of the link 84 is concentrically curved with respect to its pivot 72 for coaction with the substantially similarly-shaped forward under edge of the safety-locking finger 86 of the safety member 76.

In addition to its being provided with the two laterally-extending fingers 56 and 58 through which the firing-plunger extends, the shifting-slide 57 is also provided with a laterally-extending shifting-finger 87 which is pierced for the sliding reception of the rear end of a plate-like spring-guide or plunger 88 and which has an upstanding lug 87^a reciprocating in a guide-groove 87^b formed in the under face of the upper-tang 32 of the frame 20. Mounted upon the spring-guide 88 is a helical shifting-spring 89 bearing at its rear end against the forward face of the shifting-finger 87 and at its forward end against a forwardly-facing abutment 90 formed upon the said spring-guide 88. The forward end of the said spring-guide 88 is laterally offset and fits within a rearwardly-opening socket 91 formed in the operating-head 36 of the operating-lever 35. As thus constructed and arranged, in addition to tending to urge the shifting-slide 57 rearwardly, the shifting-spring 89 also exerts through the intermediary of the forward end of the spring-guide 88 a force to turn the operating-head 36 into position to align its operating-lever 35 with the firearm after the said operating-lever has been swung laterally to the right to retract the locking-nose 42 of the barrel-locking member 40.

For a better understanding of the operation of the parts above described, let it be presumed that the said parts are in the positions in which they are shown in Fig. 2, which are the positions which the said parts assume immediately after the firearm has been fired.

In order to prepare the gun for another shot, the operating-lever 35 may be swung laterally toward the right side of the firearm by suitable manual pressure and thus cause the operating-head 36 thereof to turn and rock the barrel-locking member 40 so as to withdraw its locking-nose 42 from the locking-notch 43 in the barrel-coupling lug 27 of the barrel 22. The described turning movement of the operating-head 36 will in addition to shifting the barrel-locking member 40 as before described, also force the spring-guide 88 rearwardly, with the effect of further tensioning the shifting-spring 89 and of causing the said spring-guide to shift the safety-slide 80 rearwardly. This rearward movement of the safety-slide will bring the rear portion of the upper end of the safety-member 76 beneath the under surface of the upper-tang 32 and out of full registration with the slot 77, thus locking the trigger 67 against further operation until the said safety-member 76 has been again shifted forwardly.

When the shifting-spring 89 is tensioned as above described it exerts an increased effort to shift the shifting-slide 57 rearwardly and hence acts through the tensioning-lever 47 to lift the rear end of the barrel 22 with respect to the frame 20. As soon now as a manual effort is made to swing the barrel-unit toward the position in which it is indicated by broken lines in Fig. 1 and by full lines in Fig. 3, the said shifting-spring 89 will act to assist this movement by urging the shifting-slide 57 rearwardly. Inasmuch as the stop-flange 55 of the firing-plunger 52 is engaged with the stop-finger 56 of the shift-

ing-slide 57, the rearward movement of the said slide 57 will carry with it the firing-plunger 52 and force the tapered cocking-head 60 thereof rearwardly so that the same forces its way beneath the cocking-finger 61 of the sear 62, which will swing upwardly until the said cocking-finger 61 is forward of the forward face of the cocking-head 60 whereupon it will swing downwardly to the position indicated in Fig. 3. The described rearward movement of the shifting-slide 57 also serves to rock the supporting-link 84 so as to bring its safety-locking finger 85 beneath the safety-locking finger 86 of the safety-member 76, with the result that the said safety-member and hence the safety-slide 80 is locked in its safety position in which the trigger 67 cannot be actuated for firing the gun until the gun is fully closed and the said safety-slide is manually moved to the limit of its forward movement.

After a fresh cartridge has been inserted into the cartridge-chamber of the barrel 22 and finger pressure has been removed from the operating-lever 35, so that the same together with the barrel-locking member 40 may reassume their normal positions, the barrel-unit may be swung into its closed position as indicated in Fig. 4. The closing movement of the barrel-unit as just referred to will depress the arm 49 of the lever 47 and cause the upstanding arm 48 thereof to forwardly force the finger 56 of the shifting-slide 57 and thereby shift the said slide forwardly. This shifting of the slide 57 will have the effect of compressing both the firing-spring 51 and the shifting-spring 89. The forward movement of the firing-plunger 52 being at this time prevented by the engagement of its cocking-head 60 with the cocking-finger 61 of the sear 62.

As the shifting-slide 57 moves forwardly as above described, the supporting-link 84 will be similarly rocked, so that its safety-locking finger 85 is moved out of the path of the safety-locking finger 86 of the safety-member 76 to permit the latter to be manually rocked forwardly when desired by means of the safety-slide 80. The parts will now have assumed the positions in which they are shown in Fig. 4, in readiness for firing the gun as soon as the operator cares to shift the safety-slide 80 forwardly and subsequently pull the trigger 67.

When the finger-piece 73 is pulled rearwardly after the safety-member 76 has been swung forwardly into full registration with the slot 77 in the upper-tang 32, the movement of the said finger-piece will rock the trigger 67 about its pivot-pin 72 and hence swing the sear 62 so as to disengage its cocking-finger 61 from the cocking-head 60 of the firing-plunger 52. The firing-plunger is thus released to the action of the now tensioned firing-spring 51 which will snap the same forwardly, with the effect of firing the cartridge in the rear end of the barrel 22.

As the firing-plunger 52 approaches the limit of its forward movement, just above described, its stop-flange 55 will engage with the rear face of the stop-finger 56 of the shifting-slide 57 and carry the same forwardly with it against the tension of the shifting-spring 89 until the said finger 56 strikes against the adjacent rear face of the barrel-locking member 40 by which the forward movement of both the firing-plunger 52 and the shifting-slide 57 will be checked. As soon as the forward movement of the shifting-slide has been checked as described, the shifting-

spring 89 will assert itself and move the said slide and the said firing-plunger rearwardly to a slight degree to the positions in which they are indicated in Fig. 2. The firearm is now in readiness for a repetition of the cycle of loading and firing as above described.

The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claims are intended to be embraced therein.

I claim:

1. A firearm including in combination: a firing-plunger; a sear for releasably holding the said firing-plunger in its cocked position; a trigger movable with respect to and controlling the said sear; a firing-spring encircling the said firing-plunger; a shiftable member having a portion positioned to limit the firing movement of the said firing-plunger; and spring-means urging the said shiftable member in a direction opposite to the firing movement of the said firing-plunger and serving to shift the said firing-plunger and the firing-spring carried thereby in the direction required to engage the said firing-plunger with the said sear.

2. A firearm including in combination: a firing-plunger; a sear for releasably holding said firing-plunger in its cocked position; a trigger movable with respect to and controlling the said sear; a firing-spring urging the said firing-plunger into its firing position; and means serving to shift the said firing-plunger into position for engagement by the said sear including a shiftable-abutment constructed and arranged to receive the thrust of the said firing-spring and engaged by the said firing-plunger for being shifted rearwardly thereby, and a spring urging the said shiftable-abutment toward the said sear.

3. A firearm including in combination: a firing-member; a sear for releasably holding said firing-member in its cocked position; a firing-spring urging the said firing-member into its firing position; and means serving to shift the said firing-member into position for engagement by the said sear including a firing-member shifter having two spaced-apart abutments, one of which abutments is engaged by the said firing-member for limiting the firing movement thereof and the other of which abutments receives the thrust of the said firing-spring, and spring-means acting through the said firing-member shifter to urge the said firing-member into position for engagement by the said sear.

4. A firearm including in combination: a firing-member; a sear for releasably holding said firing-member in its cocked position; a firing-spring carried by the said firing-member and urging the said firing-member into its firing position; and means serving to shift the said firing-member into position for engagement by the said sear including a firing-member shifter having two spaced-apart abutments, one of which abutments is engaged by the said firing-member for limiting the firing movement thereof and the other of which abutments receives the thrust of the said firing-spring, and spring-means acting through the said firing-member shifter to urge the said firing-member into position for engagement by the said sear.

5. In a breakdown firearm, the combination

with a butt-unit and a complementary barrel-unit movable with respect to the said butt-unit; of a firing-member; a sear for releasably holding said firing-member in its cocked position; a firing-spring urging the said firing-member into its firing position; means serving to shift the said firing-member into position for engagement by the said sear including a firing-member shifter having two spaced-apart abutments, one of which abutments is engaged by the said firing-member for limiting the firing movement thereof and the other of which abutments receives the thrust of the said firing-spring, and spring-means acting through the said firing-member shifter and urging the said firing-member into position for engagement by the said sear; and means operatively interconnecting the said firing-member shifter and the barrel-unit, constructed and arranged in a manner to cause the upward swinging movement of the said barrel-unit to move the said firing-member shifter away from the said sear.

6. In a breakdown firearm, the combination with a butt-unit and a complementary barrel-unit movable with respect to the said butt-unit; of a firing-member; a sear for releasably holding said firing-member in its cocked position; a firing-spring urging the said firing-member into its firing position; means serving to shift the said firing-member into position for engagement by the said sear including a firing-member shifter having two spaced-apart abutments, one of which abutments is engaged by the said firing-member for limiting the firing movement thereof and the other of which abutments receives the thrust of the said firing-spring, and spring-means acting through the said firing-member shifter and urging the said firing-member into position for engagement by the said sear; and a shifting-lever pivoted intermediate its opposite ends and operatively interconnecting the said firing-member shifter and the barrel-unit, constructed and arranged in a manner to cause the upward swinging movement of the said barrel-unit to move the said firing-member shifter away from the said sear.

7. In a breakdown firearm, the combination with a butt-unit and a barrel-unit pivoted for movement with respect to the said butt-unit; of locking-means for locking the two said units in normal alignment, including a manual operating-lever; a firing-member; a sear for releasably holding the said firing-member in its cocked position; a firing-spring urging the said firing-member into its firing position; and double-acting spring-means having one of its ends urging the said operating-lever into its locking position, and having its opposite end operatively connected with the said firing-member and urging the same into position for engagement by the said sear.

8. In a breakdown firearm, the combination with a butt-unit and a complementary barrel-unit pivoted to the said butt-unit; of a reciprocating firing-plunger; a sear for releasably holding the said firing-plunger in its cocked position; a firing-spring encircling and urging the said firing-plunger into its firing position; and a spring-abutment movable with respect to the said firing-plunger and the said firing-spring and having a portion against which the said firing-spring thrusts; connecting-means operatively connecting the said spring-abutment to the said barrel-unit and constructed and arranged to energize the said firing-spring by the relative

pivotal movement of the said barrel-unit with respect to the butt-unit.

9. In a breakdown firearm, the combination with a butt-unit and a complementary barrel-unit pivoted to the said butt-unit; of a reciprocating firing-plunger; a sear for releasably holding the said firing-plunger in its cocked position; a firing-spring encircling and urging the said firing-plunger into its firing position; a spring-abutment movable with respect to the said firing-plunger and the firing-spring and provided with a portion against which the said firing-spring thrusts; connecting-means operatively connecting the said spring-abutment to the said barrel-unit and constructed and arranged to energize the said firing-spring by the relative pivotal movement of the said barrel-unit with respect to the butt-unit; and second spring-means urging the said spring-abutment in a direction opposite to the direction in which it is shifted by the movement of the two said units.

10. In a breakdown firearm, the combination with a butt-unit and a complementary barrel-unit movable with respect to the said butt-unit; of a firing-member; a sear for releasably holding the said firing-member in its cocked position; a shiftable firing-spring tensioning-member having two spaced-apart abutments; a firing-spring urging the said firing-member into its firing position and confined between the respective abutments of the said shiftable tensioning-member; and means operatively connecting the said firing-spring tensioning-member with the said barrel-unit, whereby the movement of the latter with respect to the butt-unit effects the shifting of the said tensioning-member.

11. In a breakdown firearm, the combination with a butt-unit and a complementary barrel-unit movable with respect to the said butt-unit; of a firing-member; a sear for releasably holding the said firing-member in its cocked position; a shiftable firing-spring tensioning-member having two spaced-apart abutments; a firing-spring urging the said firing-member into its firing position and confined between the respective abutments of the said shiftable tensioning-member; means

operatively connecting the said firing-spring tensioning-member with the said barrel-unit, whereby the movement of the latter with respect to the butt-unit effects the shifting of the said tensioning-member in a direction required to cause the same to project the said firing-member forwardly; and second spring-means urging the said tensioning-member into its retired position.

12. In a breakdown firearm, the combination with a butt-unit and a complementary barrel-unit movable with respect to the said butt-unit; of a firing-member; a sear for releasably holding the said firing-member in its cocked position; a shiftable firing-spring tensioning-member having two spaced-apart abutments; a firing-spring urging the said firing-member into its firing position and confined between the respective abutments of the said shiftable tensioning-member; and a firing-spring tensioning-lever constructed and arranged to be actuated by the relative movement between the two said units and operatively connected to the said firing-spring tensioning-lever to effect the movement thereof into position for tensioning the said firing-spring.

13. In a breakdown firearm, the combination with a butt-unit and a complementary barrel-unit movable with respect to the said butt-unit; of a firing-member; a sear for releasably holding the said firing-member in its cocked position; a shiftable firing-spring tensioning-member having two spaced-apart abutments; a firing-spring urging the said firing-member into its firing position and confined between the respective abutments of the said shiftable tensioning-member; a firing-spring tensioning-lever constructed and arranged to be actuated by the relative movement between the two said units and operatively connected to the said firing-spring tensioning-lever to effect the movement thereof into position for tensioning the said firing-spring; and second spring-means urging the said firing-spring tensioning-member in a direction opposite to the direction in which it is shifted by the said tensioning-lever.

GEORGE S. LEWIS.
